CLAIM

The ornamental design for a container carrier, as shown and described.

DESCRIPTION

FIG. 1 is a perspective view of a container carrier, showing a first embodiment of our new design in a folded configuration and in a condition of use, holding two containers; FIG. 2 is a perspective view thereof, illustrated in a flat configuration;

FIG. 3 is a top plan view of FIG. 2, the bottom plan view being a mirror image thereof;

FIG. 4 is a left-side elevational view of FIG. 2, the right-side elevational view being a mirror image thereof;

FIG. 5 is a front elevational view of FIG. 2, the rear elevational view being a mirror image thereof;

FIG. 6 is a perspective view of a second embodiment in the folded configuration and in the condition of use with three of the containers;

FIG. 7 is a perspective view of FIG. 6, but with the container carrier applied upside-down to the containers and with disclaimed tabs of a top side of the container carrier omitted for clarity of illustration;

FIG. 8 is a perspective view thereof, illustrated in the flat configuration;

FIG. 9 is a top plan view of FIG. 8, the bottom plan view being a mirror image thereof;

FIG. 10 is a left-side elevational view of FIG. 8, the right-side elevational view being a mirror image thereof; and,

FIG. 11 is a front elevational view of FIG. 8, the rear elevational view being a mirror image thereof.

The dash-dash broken lines showing bottles in FIGS. 1, 6, and 7 depict environmental structure. The remaining dash-dash broken lines represent portions of the container carrier. The dot-dash broken lines represent the bounds of the claim. The broken lines form no part of the claimed design.
